UNITED STATES PATENT OFFICE

95,396

DESIGN FOR A GRAVE VAULT HOOD OR SIMILAR ARTICLE

Allen F. Beck, Columbus, Ohio

Application June 23, 1934, Serial No. 52,317

Term of patent 14 years

To all whom it may concern:

Be it known that I, Allen F. Beck, a citizen of the United States, residing at Columbus, in the county of Franklin and State of Ohio, have invented a new, original, and ornamental Design for a Grave Vault Hood or Similar Article, of which the following is a specification, reference being had to the accompanying drawing, forming a part thereof.

Fig. 1 is a perspective view of a grave vault hood or similar article, showing my new design;

Fig. 2 is a transverse vertical sectional view thereof;

Fig. 3 is a detail horizontal sectional view taken through the end of the vault hood on the plane indicated by the line III—III of Fig. 2;

Fig. 4 is a detail vertical longitudinal sectional view on the plane indicated by the line IV—IV of Fig. 2.

The dominant feature of my invention resides in the convex bulges in the upper regions of the end walls of the vault without any beading effect.

I claim:

The ornamental design for a grave vault hood or similar article, as shown and described.

ALLEN F. BECK.
